(57) **CLAIM**

What is claimed is the ornamental design for a protective garment, as shown and described.

DESCRIPTION

FIG. 1 is a front elevated view of a first embodiment of a protective garment;

FIG. 2 is a close-up of front elevated view of the first embodiment thereof;

FIG. 3 is an elevated back view of the first embodiment thereof;

FIG. 4 is a right-side elevated view of the first embodiment thereof;

FIG. 5 is a left side elevated view of a first embodiment thereof;

FIG. 6 is a front elevated view of a third embodiment of a protective garment, wherein the protective garment is integrated into an article of clothing;

FIG. 7 is a right-side elevated view of the third embodiment thereof; and,

FIG. 8 is a left side elevated view of the third embodiment thereof.

The broken lines illustrate portions of the monitoring garment and form no part of the claimed design.

1 Claim, 6 Drawing Sheets
